DRAWER PULL

Gerard N. Stelma, 1755 Millbrook SE.,
Grand Rapids, Mich.

Filed Jan. 30, 1961, Ser. No. 63,738

Term of patent 14 years

(Cl. D10—8)

FIG. 1

FIG. 2

FIG. 3

FIG. 4

FIGURE 1 is a longitudinal sectional view of a drawer pull, showing my new design;

FIGURE 2 is a plan view thereof;

FIGURE 3 is an end elevational view thereof; and

FIGURE 4 is a perspective view thereof.

I claim:

The ornamental design for a drawer pull, as shown.
